UNITED STATES PATENT OFFICE.

FRANK S. HYATT, OF BROOKLYN, NEW YORK.

TUBE COMPRESSOR.

Application filed February 4, 1921. Serial No. 442,375.

To all whom it may concern:

Be it known that I, FRANK S. HYATT, a citizen of the United States, and a resident of Brooklyn, in the county of Kings and State of New York, have invented certain new and useful Improvements in Tube Compressors, of which the following is a specification.

My invention relates to the construction of tube compressor clamps designed to apply clamping pressure by means of a cam piece provided with actuating arms, said cam piece being mounted in arms or brackets rising from a suitable base and being arranged to act upon the clamping jaw.

An example of the class of device to which my invention relates is described in the patent to A. J. Frey No. 1,217,433.

The object of my invention is to overcome a defect or drawback in the type of compressor above referred to: to wit, that there is a tendency for the compressor to come apart due to the insecure mounting of the clamping lever or cam in the arms or brackets of the clamping jaws.

A further object is to overcome this objection without adding to the cost of manufacturing the compressor.

To these ends my invention consists in the improved construction of tube compressor whereby the parts are securely fastened together as hereinafter more particularly described and then specified in the claims.

In the accompanying drawings, Fig. 1 is a side elevation of a tube compressor embodying my invention and shows the jaw open.

Fig. 2 is a plan of the same.

Fig. 3 is a front elevation of the same but showing the jaw closed.

Fig. 4 is a plan view of a modified arrangement.

My present invention is herein shown and will be described in connection with sheet metal compressors but it will be understood that it is not limited to any particular type of compressor except as may be specified in the appended claims.

In the drawings 1 and 2 indicate respectively two clamping jaws formed or con-

nected in any desired way, as for instance they may be formed of a single piece of sheet metal provided at 4 with an opening for the insertion of the tubing to be clamped.

7 indicates arms or brackets rising from the base which carries the jaw 2 and combined with or mounted upon said base in any desired way and made of any suitable material but provided, as shown near their upper ends, with openings to receive the pintles or ears 6 extending from the cam piece 5 and pivoted in said openings.

9 and 10 indicate respectively the two operating or actuating arms of the cam and which, with the cam, form the clamping lever of the compressor. The actuating arms 9, 10 permit the cam to be operated by the thumb or finger to either compress or clamp the jaw 1 or to release the same. The arms 9 and 10 and the cam are made preferably out of a single piece or strip of sheet metal which is bent up in any desired way to form the operating arms and the cam 5 which engages the jaw 1 by its free end. The clamping lever is also provided in the form illustrated with a strut or stay 11 to back up the cam 5 as described in prior patent to A. J. Frey No. 1,297,456.

In previous forms of compressors the piece or strip of metal is stamped or cut out from a sheet of metal or blank in such form that the pintles or ears 6 extend straight out from the sides of the cam 5 and project straight through the openings in the brackets 7. As there is more or less spring to the brackets 7, the ears 6 tend to slip out of the openings and dismount the cam 5 thus rendering the compressor inoperative. In some cases the straight ears, after being inserted through the openings, have been split and bent away from one another to hold them against slipping out of the openings.

It is the object of the present invention to cure this defect without rendering it necessary to slit said straight ears and bend the two parts away from one another after said straight ears have been projected through the openings in the assembling operation.

According to one way of accomplishing the object the ears 6 instead of emanating straight from the cam 5 are inclined upward as shown in Fig. 3 thus forming the hooks which can be entered or passed through the openings in the assembling operation and which, on completion of the assembly, serve to hold the cam in place. Another way is shown in Fig. 4 in which a blank or strip of sheet metal is cut in such way as to form ears which project straight from the sides of the cam but are each provided with a notch 12 in which the brackets 7 seat and a shoulder 13 which prevents the ear slipping out of the opening in the bracket. As will be seen, in this case also the ears form hooks which can be projected through the openings in the assembling operation and serve, without further manipulation, to hold the cam in place.

In both cases the piece or strip of sheet metal from which the cam is formed is cut out or stamped with ears 8 which are so initially formed on the blank of such shape that a recess is formed in which the bracket seats and as the portion of the ears which projects beyond the opening in the brackets intersects the periphery of the opening; the cam is securely held to the brackets—that is, a comparatively slight pressure outwardly on the brackets will not free the cam from its pivotal support as is the case when the ears 6 are formed as in the prior art.

35 As no additional operation or labor is necessary to form the ears according to this invention to that required in the previous forms, no increase of cost attends the use of the present improvement.

40 It will be seen that by the foregoing construction there is provided a positive means which prevents the spreading of the cam holding brackets; that in both Figs. 3 and 4 when the clamping members are in tube compressing position the cam is forced upwardly with respect to said brackets and that said brackets can not be forced apart without first riding over the hooked ears, which can not occur since the upper clamping member acts as a spring to force these ears upwardly. It will also be seen that in the construction shown in Fig. 3 the decided incline of the hooked ears tends positively to draw the brackets toward each other.

45 What I claim as my invention is:—

1. In a tube compressor, the combination of upper and lower clamping members, brackets rising from opposite sides of one of said members and an operating cam engaging the other member and having rigid ears pivoted in fixed position in openings in said brackets, said ears being stamped out of the sheet metal of the cam integral therewith and of a form adapting them

without bending to act as hooks on being entered in said openings in the assembling operation.

2. In a tube compressor, the combination of upper and lower clamping members, brackets rising from opposite sides of one of said members and an operating cam engaging the other member and having rigid ears pivoted in fixed position in openings in said brackets, said ears being stamped in the form of hooks from the sheet metal of the cam and integral therewith and which on being entered on assembly in said openings will hold the cam in place.

3. In a tube compressor, the combination of upper and lower clamping members, brackets rising from opposite sides of one of said members and an operating cam engaging the other member and having rigid ears struck up as hooks from the sheet metal of the cam integral therewith and pivoted in fixed position in openings in said brackets, said ears operating on being hooked into said openings on assembly and without bending to hold the cam against displacement.

4. In a tube compressor, the combination of upper and lower clamping members, brackets rising from opposite sides of one of said members and an operating cam engaging the other member and having rigid ears pivoted in fixed position in openings in said brackets, said ears being initially formed on the cam with an upward inclination permitting them to be entered after formation in the openings and thereafter to act as hooks to hold the cam against displacement, as and for the purpose described.

5. In a tube compressor, the combination of upper and lower clamping members, brackets rising from opposite sides of one of said members and having openings therein, an operating cam engaging the other member, said cam having hooked ears inserted in said openings, said hooked ears being adapted under the action of one of said members to force said brackets toward each other in the clamping act.

6. In a tube compressor, the combination of upper and lower clamping members, brackets rising from opposite sides of one of said members and having openings therein, an operating cam engaging the other member, said cam having hooked ears adapted to be inserted in said openings in the assembling operation and adapted in their original form, under the action of one of said clamping members, to prevent spreading of said brackets.

7. In a tube compressor, the combination of upper and lower clamping members, brackets rising from opposite sides of one of said members and having openings therein, an operating cam engaging the

other member, said cam having hooked ears stamped out thereof in the same plane therewith and adapted to be inserted axially through said openings in the assembling 5 operation, said ears being adapted, in their original form, under the action of one of said clamping members, to prevent spreading of said brackets when said clamping

members are in tube compressing position.

Signed at Brooklyn in the county of 10 Kings and State of New York this 2d day of February A. D. 1921.

FRANK S. HYATT.
